UNITED STATES PATENT OFFICE

2,515,606

CONTINUOUSLY ACTUATED ONE
REVOLUTION CLUTCHVictor F. Linder, Minneapolis, Minn., assignor to
Albert T. O'Neil, Minneapolis, Minn.

Application June 18, 1945, Serial No. 600,118

7 Claims. (Cl. 74—125.5)

1

My invention relates to power driven tools and particularly to tools similar to punches and shears in which a reciprocating member or cross-head or ram is cyclically operated to give said cross-head a power stroke and a return stroke.

An object of the invention resides in providing a power tool of such nature in which a constant time is required for performing the power stroke and return stroke and in which varying periods of rest occur between cycles to vary the number of operations in a given unit of time without affecting the performance of the tool.

Another object of the invention resides in providing the tool with a continuously rotating driving member and in further providing connecting means between said member and cross-slide, whereby the cross-slide may be reciprocated during a rotation of said member and in which connection of said cross-slide to said driving member terminates upon completion of the return stroke of the cross-head.

An object of the invention resides in providing timing means acting upon said connecting means to control the operation thereof.

Another object of the invention resides in providing a device actuated by the cross-head on its return stroke for energizing the timing means.

A still further object of the invention resides in utilizing a dash pot as the timing means and in providing means for resetting said dash pot by the cross-head upon its return stroke.

A feature of the invention resides in utilizing a crank shaft for operating said reciprocating member and in providing a clutch between said driving member and shaft and in controlling the disengagement of said clutch by said timing means.

An object of the invention resides in providing an arm for operating said clutch and a lever for moving said arm and in further connecting said dash pot to said lever.

Other objects of the invention reside in the novel combination and arrangement of parts and in the details of construction hereinafter illustrated and/or described.

In the drawings:

Fig. 1 is a fragmentary side elevational view partly in section of a power driven shear illustrating an embodiment of my invention applied thereto.

Fig. 2 is an elevational vertical transverse sectional view taken on line 2—2 of Fig. 1.

Fig. 3 is a view similar to Fig. 2 showing the parts in altered position.

2

Fig. 4 is an elevational longitudinal sectional view of the dash pot used with the invention.

In the use of power driven shears, punches and similar tools, in which a reciprocating cross-head or ram is employed, it becomes highly desirable to control the number of operations rendered by the machine in a given time. Heretofore, this has been accomplished by changing the speed of the machine. The result has been that the length of time employed in performing the operation has also been varied, with the result that the performance has not been uniform. The instant invention overcomes this disadvantage by providing a power driven tool in which the same length of time is required for the performance of each operation, but in which the period of rest between operations can be varied to produce any number of operations in a given time.

For the purpose of illustrating my invention, 20 I have shown in the drawings a portion of a shear indicated in its entirety by the reference numeral 10. Inasmuch as power driven shears are well known in the art, only a portion of the shear has been shown in detail. The shear 10 comprises a base 11 which has issuing upwardly from it two guides, one of which is shown in the drawings and designated by the reference numeral 12. A cross-head 13, having bosses 14 thereon slidable along the said guides, is guided by and movable in a vertical direction toward and from the base 11. The base 11 has attached to it a fixed shear blade 15, while the cross-head 13 has attached to it a shear blade 16 movable toward and from the shear blade 15.

Attached to the upper ends of the guides 12 are bearings 17 which rotatably support a shaft 18. Shaft 18 has eccentrics 19 secured to the same. Cooperating with these eccentrics are eccentric straps 21 which are pivotally connected to clevises 22 secured to the cross-head 13. It will thus become readily comprehended that when the shaft 18 is rotated, cross-head 13 has imparted to it a power stroke during which the blade 16 cooperates with the blade 15 to shear material placed therebetween and that said cross-head further has imparted to it a return stroke in which the blade 16 is moved away from the shear blade 15.

Attached to the shaft 18 adjacent one end of the bearing 17 and abutting against the outer face 23 thereof is a collar 24 which is keyed to said shaft by means of a key 25. Adjacent this collar and rotatably mounted on the protruding end 20 of the shaft 18 is a fly-wheel 26 which is held in place adjacent the collar 24 by means of an-

other collar 27. The collar 27 is attached to the end 20 of shaft 18 by means of a set screw 28. Fly-wheel 26 is driven by means of a belt 29 passing over the same and serves as the driving member of the tool. When the fly-wheel 26 is connected to the shaft 18, the said shaft reciprocates the cross-head 16 which becomes the driven member of the tool.

For affecting a driving connection between the flywheel 26 and the shaft 18, a clutch, indicated in its entirety by the reference numeral 31, is employed. This clutch comprises an elongated key 32 which is slidable along a longitudinal groove or guideway 33 formed in the collar 24. The key 32 slides in this groove and rests upon the outer surface of the portion 20 of shaft 18. The end 34 of key 32 is adapted to enter into either of two notches 35 formed in the inner face 36 of the hub 37 of fly-wheel 26 and forming abutments for engagement with said key. The key 32 is urged toward the fly-wheel 26 by means of a coil spring 38 having a relatively few number of convolutions. This coil spring is mounted in an annular groove 39 formed in the end of the collar 24 and intersecting the guideway 33. The spring 38 is seated at one end against the face 23 of bearing 17 and at its other end against the end of the key 32 opposite the engaging portion 34 thereof.

For the purpose of controlling the operation of the clutch 31, an arm 41 is employed, best shown in Figs. 1 and 2. This arm is pivoted by means of a stud 42 to the base 11 of the shear and extends upwardly and diagonally therefrom toward the collar 24. The upper end 43 of said arm is received within an annular groove 44 in the outer periphery of said collar and fits snugly therein so that the upper portion of the arm 41 is restrained from lateral movement by the collar 24. The end 43 of the arm 41 is beveled, as best shown in Fig. 1, and has a sharpened point 50 at the outer end thereof. The end 43 of the arm 41 is adapted to enter into a notch 45 in the key 32 engaging the shoulder formed thereby and, due to the bevel of the said end of the arm, is adapted to shift the key 32 toward the left as viewed in Fig. 1, against the action of the spring 38. When the key has been so shifted, the portion 34 thereof is withdrawn from engagement with the notches 35 in fly-wheel 26, and the clutch 31 becomes disengaged, the fly-wheel 26 rotating freely upon the end 20 of shaft 18.

Pivoted to the base 11 at a locality opposite the stud 42 is a link 46 which extends upwardly toward the arm 41. This link is mounted on a stud 47 similar to the stud 42. The link 46 has pivoted to it by means of a bolt 48 a lever 49 which is also pivoted to the arm 41 by means of a bolt 51. The lever 49 may swing from its extreme positions as shown in Figs. 2 and 3. When in the position shown in Fig. 2, the end 43 of arm 41 is in a position to engage the notch 45 in key 32. When in the position shown in Fig. 3, the said portion of the arm is out of the path of travel of key 32. It will be noted that the extreme end 63 of the link 46, which is indicated at 52, serves as an abutment for engaging the arm 41 and thus limits movement of the said arm to the position shown in Fig. 3. The arm 41 and link 46 are normally urged into the position shown in Fig. 3 by means of a tension coil spring 53 which is secured to both said link and arm.

Operating in conjunction with the link 46 and lever 49 is a dash pot 54 shown in detail in Fig. 4. This dash pot comprises a cylinder 55 having a

head 56 integral therewith. Within the cylinder is slidably mounted a piston 57 making a fairly close fit with the cylinder. This piston has a connecting rod 58 screwed into the same and which terminates in an eye 59. The said piston has a number of openings 61 extending longitudinally through the same which openings are closed at their outer ends by means of a valve disk 62 seated upon the outer end 63 of said piston. This valve disk encircles the connecting rod 58 and is urged into closing position by means of a compression coil spring 64 also encircling the connecting rod 58. The coil spring 64 is seated at its outermost end against a washer 65 held in adjusted position on the connecting rod 58 by means of a pin 66. The pin 66 is insertable into any one of a number of holes 67 whereby the pressure exerted by the spring 64 may be adjusted.

The dash pot 54 is provided with a leakage passageway 68 which communicates with the interior of the cylinder 55 and with the atmosphere. This passageway is adapted to be closed by an adjusting screw 69 having a head 71 accessible from the exterior. By manipulation of the screw 69, the time required for the piston 57 to move from its inner end toward its outer end may be predetermined and varied.

The dash pot 54 is mounted on a bracket 72 integral with and extending outwardly from the link 46. A bolt 73 passes through the end of said bracket and through a hole 74 in the head 56 of cylinder 55. In this manner, the said cylinder is pivoted for oscillating movement on the bracket 72. A bolt 74 extends through the lower end of an arm 75 of lever 49 and through the eye 59 of connecting rod 58. This bolt pivotally connects the said connecting rod to the lever 49. It will readily be comprehended that relative movement of the lever 41 and link 46 from the position shown in Fig. 2 to that shown in Fig. 3 is motivated by the spring 53, but that such movement is timed by the leakage of air from the atmosphere and into the cylinder 55 through passageway 68, as the piston 57 travels from its innermost position to that shown in Fig. 4. On the return movement of the piston 57 towards its innermost position, air is forced through the passageways 61 and past the valve disk 62, permitting the piston to be quickly moved toward its inner position and the dash pot to be reset.

For the purpose of moving the arm 41 from its position shown in Fig. 3 to that shown in Fig. 2, the following construction is employed. Mounted on the bolt 48 is a roller 76. This roller is adapted to be engaged by a cam 77 secured to the cross-head 13 by means of screws 78. The cam 77 has a cam surface 79 which engages the roller 76 and swings the lever 49 outwardly, while the cross-head 13 travels from its uppermost to its lowermost position.

The operation of my invention is as follows: Assuming that a power stroke of the shear has been made and that the shear cross-head is traveling up. The parts would then be arranged as shown in Fig. 1 with the end 34 of key 32 engaged with one of the notches 35 of fly-wheel 26 and the said fly-wheel driving the shaft 18. It will be noted that the notch 45 in key 32 intersects the groove 44, as best shown in Fig. 1, when the key 32 is fully engaged with the notch 35 of fly-wheel 26. When the shaft 18 turns over sufficiently, the sharpened end 43 of the arm 41 enters the notch 45 and shifts the key 32 against the action of the spring 38 toward the left, as

viewed in Fig. 1, until the engaging end 34 is moved out of the notch 35 in said fly-wheel. Spring 53 is now urging the arm 41 to move outwardly toward the position shown in Fig. 3, which movement is timed by the dash pot 54. When arm 41 reaches the position shown in Fig. 3, the arm 41 becomes disengaged from the key 32 and spring 38 urges said key toward the fly-wheel 46. As soon as one of the notches 35 reaches a position opposite the key 32, the end 34 of said key is forced into said notch and a drive is effected for the shaft 18. The shaft 18 now rotates in a counterclockwise direction, as viewed in Figs. 2 and 3, moving the cross-head 13 downwardly. During such downward movement, the cam 77 engages roller 76 and the arm 41 is moved back into the position shown in Fig. 2. The cam 77 is so arranged that such movement does not occur until the key 32 is out of the way of the end 43 of arm 41. When the shear reaches its lowermost position, the parts are arranged as shown in Fig. 2. As the shaft 18 continues to rotate, key 32 is moved from the position shown in Fig. 2 to that shown in Fig. 3, while the arm 41 is still in the position shown in Fig. 2. During such movement, the point 50 of the end 43 of said arm enters the notch 45 and disengages the key from the fly-wheel 26, permitting the same to again idle on the shaft 18. The operation is again repeated after the dash pot 54 permits the spring 53 to bring the parts to the position shown in Fig. 2. It will readily be comprehended that the length of time required to operate the shear depends upon the speed of rotation of the fly-wheel 26 and is independent of the controlling mechanism. It will also readily become comprehended that the period of dwell between operations of the shear is controlled by the dash pot 54 and that the timing procured by the dash pot may be controlled by the screw 69. Thus, any number of operations within the limits of the device may be procured for a unit of time, so that the rapidity of time with which the machine operates may be readily controlled.

The advantages of my invention are manifest. The shear operates at the same speed, regardless of the number of operations performed during a period of time. The shear performs a single operation and then automatically stops until the timing mechanism sets it into operation again. By means of the adjusting screw on the dash pot, the period of dwell between operations can be varied to give any number of operations within the limits of the device within a given length of time. Such an adjustment can be made while the machine is running. The device is extremely simple and has no complicated or delicate parts to get out of order. The invention may be readily applied to existing machines without material alteration or reconstruction thereof.

While I have explained the invention as particularly adaptable for use with a power driven shear or punch press, it can readily be comprehended that the device can be used for other purposes and in connection with other similar devices.

Changes in the specific form of my invention, as herein disclosed, may be made within the scope of what is claimed without departing from the spirit of my invention.

Having described my invention, what I claim as new and desire to protect by Letters Patent is:

1. In a power driven tool, a cyclically operated driven member, a continuously rotating driving member, a clutch for connecting said driven

member with said driving member, an arm for periodically controlling the engagement of said clutch to effect a drive between said driving member and said driven member and for controlling the disengagement of said clutch at the end of a cycle of operation of said driven member, a lever connected to said arm and operating to swing the same from clutch-engaging to clutch-disengaging position and a dash pot connected to said lever and controlling the movement thereof in which the arm is moved to clutch-engaging position.

2. In a power driven tool, a cyclically operated driven member, a continuously rotating driving member, a clutch for connecting said driven member with said driving member, an arm for periodically controlling the engagement of said clutch to effect a drive between said driving member and said driven member and for controlling the disengagement of said clutch at the end of a cycle of operation of said driven member, a lever connected to said arm and operating to swing the same from clutch-engaging to clutch-disengaging position, a dash-pot connected to said lever and controlling the movement thereof in which the arm is moved to clutch-engaging position, and means operated by said driven member for resetting said dash-pot.

3. In a power driven tool, a base, a driven member supported on and movable relative to said base, a continuously rotating driving member carried by said base, a clutch for connecting said driven member with said driving member, an arm pivoted to said base and controlling the engagement of said clutch to affect a drive between said driving member and said driven member and for controlling the disengagement of said clutch when said driven member reaches a certain position relative to said base, a link pivoted to said base, a lever pivoted to said link and to said arm, said lever, upon swinging movement, causing the arm to move from clutch-engaging to clutch-disengaging position and a dash-pot connected to said lever.

4. In a power driven tool, a base, a driven member supported on and movable relative to said base, a continuously rotating driving member carried by said base, a clutch for connecting said driven member with said driving member, an arm pivoted to said base and controlling the engagement of said clutch to affect a drive between said driving member and said driven member and for controlling the disengagement of said clutch when said driven member reaches a certain position relative to said base, a link pivoted to said base, a lever pivoted to said link and to said arm, said lever, upon swinging movement, causing the arm to move from clutch-engaging to clutch-disengaging position and resilient means acting between said link and arm for moving said arm into clutch-engaging position and a dash pot connected to said lever and opposing such movement.

5. In a power driven tool, a reciprocating driven member having a power stroke and a return stroke, a continuously rotating driving member, a shaft, a crank connected to said shaft and operating said reciprocating member, a clutch between said driving member and shaft, control means for periodically controlling the engagement of said clutch to affect a drive between said driving member and shaft and controlling the disengagement of said clutch at the end of the return stroke of said reciprocating member, time controlled means acting on said control member to determine the period during which said

driven member remains inactive and means actuated by said reciprocating member during its power stroke for energizing said time controlled means.

6. In a power driven tool, a base, a reciprocating member mounted for movement relative to said base and having a power stroke and a return stroke, a shaft, a crank connected to said shaft and operating said reciprocating member, a continuously rotating driving member, a clutch between said driving member and shaft, an arm pivoted to said base and controlling the engagement of said clutch to effect a drive between said driving member and shaft and for controlling the disengagement of said clutch upon completion of the return stroke of said reciprocating member, a link pivoted to said base and connected to said arm, a dash-pot connected to said link and timing the movement of said arm in its movement toward clutch-engaging position and means carried by said reciprocating member and operating to move said arm into clutch-disengaging position and to reset said dash-pot.

7. In a power driven tool, a reciprocating driven member having a power stroke and a return stroke, a continuously operating driving member, normally inactive connecting means for connect-

15
10

ing said driving member with said driven member to procure operation of said driven member, control means for periodically rendering said connecting means active to effect a drive between said driving and driven members and for rendering said connecting means inactive at the end of a cycle of operation of said driven member, time controlled means acting on said control means to determine the length of the period during which said driven member remains inactive, resilient means for energizing said time controlled means and tensioning means for tensioning said resilient means and operated by said driven member during the power stroke thereof.
